APPARATUS FOR EXTRUDING METALS

Conrad C. Jacobson, Glen Ridge, N. J., assignor
to John Robertson Co., Inc., Brooklyn, N. Y.,
a corporation of New York

Application July 30, 1932, Serial No. 626,442

2 Claims. (Cl. 207—2)

The present invention relates to an apparatus for extruding metals, and more particularly to the apparatus for melting lead and lead alloys, and filling the extruding cylinder of a lead cable press and the like with such molten metal free from oxides.

In the art of extruding lead, lead alloys and the like, the presence of oxides of lead in the melting pot and in the extrusion cylinder have always proven objectionable, and when such oxides are trapped into the lead which sheathes a cable it is a known fact that they cause weakness in said sheath which materially impairs the usefulness of the cable. Care is accordingly exercised and various means have been devised in seeking to reduce to a minimum the formation of such objectionable oxides during the melting and extruding of lead.

According to the present invention I accomplish these ends through the employment of a novel kettle or chamber in which the lead is melted in an atmosphere of an inert or non-oxidizing gas and the provision of means for introducing such gas into the lead delivery tube around the draw-off valve and into the extrusion cylinder of the press, so that when said cylinder is being filled with lead preparatory to extruding the metal, said metal will flow through this inert or non-oxidizing gas-charged space out of contact with the air and thereby practically eliminate and reduce to a minimum the formation of the objectionable oxides. The means which I employ and the method which I follow will be fully understood from the detailed description which follows, when considered in conjunction with the accompanying drawings which show a preferred embodiment of my invention, and wherein

Figure 1 is a side elevation of a lead cable press and lead melting kettle, parts thereof being shown in section to better illustrate the construction thereof.

Fig. 2 is a section taken substantially along the planes of the broken line 2—2 of Fig. 1.

Fig. 3 is a section taken substantially along the plane of the broken line 3—3 of Fig. 1, showing the position of the delivery chute when the extrusion cylinder is ready to receive the ram.

Fig. 4 is an enlarged view of the draw-off valve, delivery tube and associated parts.

Referring to the drawings, I have shown the invention as applied to a cable covering press indicated generally by the reference character A, and having a reciprocating ram a which is movable within an extrusion cylinder a' to

sheathe lead cable which is drawn through a die-block a², the type of cable press and its manner of operation being well known are not here described in detail.

Mounted in close proximity to the cable press A is a lead melting pot or kettle B suitably mounted above a fire-box C within a housing D lined with fire-brick d and heat insulating brick d', there being a firing hole D' in the lower portion of said wall.

The melting pot or kettle B is preferably constructed of welded steel plates and is equipped with a draw-off spout b which extends through the wall of the kettle somewhat above the bottom thereof and is of a length to extend inwardly into the kettle to a point near the center thereof so that in drawing off the melted lead from the kettle, said molten metal will be drawn from approximately the center of the melting pot, and the possibility of drawing off dross or foreign matter which may have accumulated on the sides of the melting pot will thereby be avoided or reduced to a minimum. The draw-off spout b is preferably welded into the wall of the melting pot and extends outwardly therefrom to a point within the enclosing wall D provided with an opening d³, through which extends the end of a delivery tube E having an offset spout e extending outwardly and downwardly through the wall D. The draw-off tube b is secured to the delivery tube E by screw-threads or other equivalent means. Suitably supported by the delivery tube E is the draw-off control valve F which is mounted at one end of a valve stem f which screw-threadedly engages within a bushing f' and slidably passes through a packed joint f², the bushing f' and packing gland f² being suitably carried by the delivery tube E. At the outer end of the valve stem f is a hand wheel f³ for manipulating the valve. Disposed on the outer side of the wall D around the opening d³ and enclosing the delivery tube E and draw-off valve F is a guard plate G which serves to protect an operator from the heat and flame within the firebox and which extends up around the kettle B, the draw-off spout b, the delivery tube E and draw-off valve F.

The kettle B extends upwardly beyond the top of the enclosing wall D, upon which it is suitably supported in any approved manner, such, for example, by having an encircling channel member b' which is welded thereto, seating upon an annular flange d⁴ upon a wall cap ring d⁵. A suitably insulated closure or cover member H is provided for the kettle B, which cover member has

a vent opening through which extends a valve tube h fitted with a relief valve h^4 , a gas inlet opening through which extends the pipe h' , an inspection opening h^2 suitably protected with a glass cover, and openings h^3 in which electric illuminating means can be disposed so that the interior of the kettle above the surface of the molten lead might be illuminated for inspection through the opening h^2 . Also extending through the cover H and terminating in spaced relation to the bottom of the kettle B is a cylindrical metal tube J , the bottom of which is provided with a grate j , which tube serves as a melting chamber for the lead. The purpose of this melting chamber is to receive the pigs of new lead which are delivered to this melting chamber on a roller conveyor K past a chain guard l carried by a charging hood L which is mounted directly over the melting chamber J . The lead in this melting chamber melts at the lowest possible temperature, and because the lead at the top of this melting chamber is only slightly above the melting point of lead, very little dross or oxides are formed, and these are easily skimmed off and are thereby prevented from going down through the grate j into the melting kettle B . The grate j also prevents the pigs of new lead from passing through the melting chamber J in unmelted condition into the kettle B .

To prevent the formation of lead oxides within the kettle B , provision is made for introducing and maintaining in the kettle above the surface of the molten metal an inert or non-oxidizing atmosphere, such as carbon dioxide. The carbon dioxide or other non-oxidizing gas may be supplied to the kettle from a commercial tank of such gas M through the conducting pipe m and m' into an expansion tank N , and then through the pipe h' into kettle B . The expansion tank N is designed to keep a constant supply of the gas in the melting pot above the molten metal, and sufficient pressure is maintained in the tank N so that as the level of the molten metal recedes, the inert gas flows into the melting pot, and as the metal level rises, the inert gas is forced back into the tank N . The relief valve h^4 may be used to relieve the gas pressure in the kettle and tank N should the same become excessive. To prevent the escape of gas from the kettle B or any entrance of air thereinto, all the joints are sealed either by welding, by asbestos gaskets, or other means known to engineering science. To also eliminate the possible danger from moisture and the oxygen contained therein gaining access to the interior of the kettle, bone dry carbon dioxide or other thoroughly dried inert or non-oxidizing gas is used.

Provision having been made for maintaining the molten metal in the kettle B free from oxides, it is necessary to preserve the metal in this condition until after it is introduced into the extrusion cylinder a' . To accomplish this I have provided means whereby the molten metal, as it is being withdrawn from the melting pot and conveyed to the extrusion cylinder, will be surrounded or will move in an atmosphere of inert gas, and to further insure against this metal becoming oxidized upon reaching the extrusion cylinder I have provided means for charging said cylinder with the inert gas which is displaced as the metal flows into said cylinder. I will now describe the means whereby I accomplish this.

The supply of inert gas for this purpose is obtained from the tank M through the tube m through control valve O' into expansion tank O

wherein sufficient pressure is maintained to provide for a charge of gas for the lead cylinder when it is required. The gas to be supplied to the lead cylinder and for providing the inert gas atmosphere around the molten lead while it is being charged into said cylinder is preferably pre-heated so as to avoid loss of temperature and too rapid cooling of the molten metal as it is being introduced into the cylinder. This preheating is accomplished by passing the gas through a heating coil P which is located in the lining of the encircling wall D of the melting furnace. The discharge end of this heating coil is connected by a pipe p , a valve p' and a discharge tube p^2 , to an annular groove p^3 in the delivery tube E and connecting with the offset portion e thereof, from whence it passes down through the delivery chute R into the extrusion cylinder a' .

The delivery chute R at its upper end is pivoted to the open end of the spout e of the delivery tube E and forms therewith a tightly closed pivoted joint, and at its opposite end it is provided with a cap-like closure r of a size to substantially, but not entirely, cover the opening at the top of the extrusion chamber a' , and mounted to slidably engage over the top of said chamber.

From the constructions and arrangements of the draw-off tube b , the delivery tube E , the draw-off valve F , the gas supply means O , P , p' and p^2 , and the delivery chute R , it will be apparent that I have provided means for selectively charging the lead cylinder with molten metal, with the gas, or with both the metal and the gas simultaneously, as desired. And as it is necessary in the operation of the device to resort to these selective controls, I will now describe the cycle of operations that is followed in the operation of the present invention. The kettle B being filled with molten lead to its normal level indicated by the dotted line x (Fig. 1) and there being an atmosphere of inert gas above the surface of the metal in said kettle, gas is admitted through control valve O' into the expansion tank O until a predetermined pressure is indicated therein by the gauge o attached thereto. During this time the valve p' is kept closed. At the end of the extrusion cycle when the extrusion ram a and the extrusion lead cylinder a' are in their positions, as indicated in Fig. 1, the delivery chute R is moved into the position shown and the valve p' is opened. This admits the hot carbon dioxide to the lead delivery tube E and thence down through the delivery chute R to the extrusion cylinder a' under sufficient pressure and in sufficient quantity to displace all the free air or oxygen from said cylinder. The lead draw-off valve F is then opened by rotating the hand wheel f^3 which moves the valve plug F away from its seat in the draw-off tube b , thereby admitting lead from substantially the center of the melting pot B to the delivery tube E , delivery chute R and extrusion cylinder a' . These latter three parts having been previously filled with carbon dioxide, the lead does not come in contact with the free air or oxygen, and accordingly no oxides can be formed. When the extrusion cylinder a' has been filled, the delivery chute R is moved to one side as shown in Fig. 3 and the extrusion started. Valve p' is now closed and valve O' opened, thereby admitting a new charge of carbon dioxide to the expansion tank O and coil P to be preheated and made ready for the next filling operation of the extrusion cylinder.

From the foregoing detailed description it will

be apparent that I have disclosed a mechanism and method particularly adapted for the purpose of supplying molten lead free from oxides to the extrusion cylinder of a cable press, and although 5 the present device is primarily directed to this particular use, it is to be understood that the invention is capable and susceptible of miscellaneous uses where oxide-free molten metals are required for further treatment. Accordingly I 10 do not desire that my present invention be limited to the particular use to which I have herein made reference, nor to the specific details of construction for the various parts as disclosed, since the same may be varied within the range of 15 engineering skill without departing from the spirit of my invention.

What I claim is:

1. In combination, an extrusion press cylinder, a melting kettle, a source of non-oxidizing gas, 20 means for selectively charging said cylinder with molten metal, gas, or both metal and gas simul-

taneously, said means comprising a delivery chute having connection with both the melting kettle and the source of gas, and means surrounding the melting kettle and adapted to derive heat therefrom for preheating the gas.

2. In combination, an extrusion press cylinder, a melting kettle, a source of non-oxidizing gas, means for selectively charging said cylinder with molten metal, gas, or both the metal and gas simultaneously, said means comprising a delivery 10 chute having connection with both the melting kettle and the source of gas, and independently operable valves in the connecting means leading from the melting kettle and from the gas source respectively, the valve which controls the flow of 15 molten metal from the melting kettle to the delivery chute being outside the melting kettle and exposed to the same source of heat that melts the metal within the melting kettle.

CONRAD C. JACOBSON.
